PORTABLE CURRENT INTENSITY DETECTOR FOR AERIAL BOOMS

Paul E. Skarshaug, 4607 Dover Drive,
Ames, Iowa 50010

Filed Oct. 27, 1969, Ser. No. 19,741

Term of patent 14 years

Int. Cl. D10—10

U.S. Cl. D26—1

Fig. 1

Fig. 3

Fig. 4

Fig. 2

Fig. 5

Fig. 6

FIG. 1 is a perspective view of the portable current intensity detector for aerial booms showing my new design;

FIG. 2 is a top plan view thereof;

FIG. 3 is an end elevational view thereof as seen from the left-hand end of FIG. 2;

FIG. 4 is an elevational view thereof as seen from the right-hand end of FIG. 2;

FIG. 5 is a side elevational view thereof, the opposite side being a mirror image thereof; and

FIG. 6 is a bottom plan view thereof.

I claim:

The ornamental design for a portable current intensity detector for aerial booms, substantially as shown.
